DESIGN FOR A CHILD'S PLAY SUIT

Mary Jacques, New York, N. Y.

Application April 8, 1937, Serial No. 68,633

Term of patent $3\frac{1}{2}$ years

To all whom it may concern:

Be it known that I, Mary Jacques, a citizen of the United States, residing in New York, in the county of New York and State of New York, have invented a new, original, and ornamental Design for Child's Play Suit, of which the following is a specification, reference being had to the accompanying drawing forming a part hereof in which

The skirt is detachable, as indicated in the drawing.

I claim:

The ornamental design for a child's play suit substantially as shown and described.

MARY JACQUES.
